UNITED STATES PATENT OFFICE.

FRANK W. CHRISTY, OF BEVERLY, MASSACHUSETTS, ASSIGNOR TO UNITED SHOE MACHINERY CORPORATION, OF PATERSON, NEW JERSEY, A CORPORATION OF NEW JERSEY.

SKIVING MACHINE.

Application filed May 24, 1920. Serial No. 383,772.

To all whom it may concern:

Be it known that I, FRANK W. CHRISTY, a citizen of the United States, residing at Beverly, in the county of Essex and State of Massachusetts, have invented certain Improvements in Skiving Machines, of which the following description, in connection with the accompanying drawings, is a specification, like reference characters on the drawings indicating like parts in the several figures.

This invention relates to the treatment of leather or similar sheet material in a manner to skive the edge thereof and at the same time to render the material of uniform thickness at and adjacent to the base of the scarf.

In practising the method of finishing the edge of a piece of leather, set forth in the patent to Halsey and Perkins No. 1,047,211, in which the extreme margin on one side of the leather (usually the flesh side) is subjected to the action of a shrinking agent such as heat so as to cause the other side to curl toward the shrunken side, it has been found advantageous, when the leather is thick or of a hard, refractory nature, to prepare the leather for the shrinking operation by producing a comparatively abrupt scarf on its edge, a machine adapted to produce such a scarf being shown in the patent to Enslin, No. 1,358,140. Even after the leather has been thus skived, however, it happens in many cases that the searing operation will not produce the best results unless the leather in the locality at the base of the scarf is of uniform thickness or substantially so throughout the piece.

According to the present invention, in addition to the removal of stock to produce the abrupt scarf, stock is removed at and adjacent to the base of the scarf in such manner that, in the finished piece, the material in the locality at the base of the scarf is rendered of substantially uniform thickness if it was not so originally; and conveniently this desired uniformity of thickness at the particular locality named may be secured by producing a scarf of gradual inclination adjoining the abrupt scarf.

In the illustrated machine, I provide in connection with a skiving knife a special feed roll having a circular rib thereon, and

a presser foot having a notch to receive this peripheral rib. The function of the rib is 55 to force the edge of the leather out of the plane of the body portion as it reaches skiving position so that when the skived leather is returned to its normal position, the result is the formation of two adjacent bevels having different inclinations an abrupt one at the extreme edge of the leather and a gradual one adjoining it.

Another object is to provide improved means to hold the work against the feed roll 65 and, in the illustrative embodiment, a pair of independently movable presser feet are provided. Thus, if the leather is not of uniform thickness, one of the presser feet may give somewhat when a thick spot is encountered while the other continues to press firmly on the remainder of the material.

Referring to the drawings.

Fig. 1 is a perspective view of a portion of a machine for producing the desired result, 75 the driving mechanism being omitted.

Fig. 2 is a longitudinal sectional view through the feed roll and presser feet.

Fig. 3 is an enlarged front elevation showing the position of the work when being 80 skived.

Fig. 4 is a detail perspective view of the edge gage and the carrier member for the presser feet.

Fig. 5 is a perspective view indicating the 85 condition of the work when skived and restored to a flat position.

The numeral 2 indicates the disk knife and 4 the feed disk which may be driven in any suitable manner as disclosed, for example, in patent to Bayley No. 823,578. Upon the frame 6 of the machine is a bearing 8 for the drive shaft 10 of the feed roll 12 which replaces the usual feed roll on the machine. This feed roll is formed, preferably, with a frusto conical feed surface 14 which is nearly parallel with the cutting edge of the knife and a peripheral rib or projection 16 is formed on the feed roll near the inner edge. Secured to a boss on the bearing 8 by a screw 19, is a gage support 18 having a horizontal portion to which is secured a gage member 20. This gage member is provided with a guide arm or edge gage 26 which is curved to fit the periphery 105 of the feed roll, the gage member having

a slot 22 by which it may be adjustably secured to the gage support, a suitable thumb screw 24 being provided for this purpose. This gage member is also provided with a longitudinal guideway 28 to receive a guide rib 30 on an adjustable carrier plate 32 which carries a plurality of presser feet. The carrier plate has a depending flange 34 at one end and a thumb screw 36 rotatably engaged this flange and is threaded into the gage member 20 to provide for longitudinal adjustment of the carrier plate. A guide screw 39 is threaded into the gage member and engages a slot 38 in the carrier plate to serve as a guide for the latter.

Secured to the carrier plate by a screw 44 is a spring tongue 40 for a presser foot 42 which holds the material against the feed roll and prevents injury to the body portion. This spring tongue has threaded therein a thumb screw 46 which abuts at its lower end against the carrier plate 32 and serves as a means for adjusting the presser foot 42 with reference to the feed roll to provide for different thicknesses of stock. Extending upwardly from the carrier plate is a guide pin 48 which passes through a slot in the spring tongue 40 and serves to keep the latter in alignment with the adjacent parts.

Secured in a rectangular slot of the spring tongue 40 by means of screws 52, is a spring tongue 50 carrying at its outer end a presser foot 56 which engages the material adjacent the edge and holds it against the feed roll. This spring tongue 50 is guided vertically by a guide pin 54 secured to the carrier plate and projecting upwardly through a slot in the spring tongue. The presser foot 56 is provided on its inner lower edge with a notch 58 to receive the peripheral rib or projection 16 on the feed roll and the vertical movement of the spring tongue may be limited by a thumb screw 60 which is threaded into the spring tongue and carries a collar 62 to engage the gage member 20. The vertical movement of the spring tongue in a downward direction may be adjusted by means of a thumb screw 64 threaded into the spring tongue and abutting at its end against the carrier plate 32. The provision of the two independently movable presser feet 42 and 56 renders it possible for one of them to pass over an uneven portion of the leather without affecting the firm pressure of the other on the material.

In the operation of the machine, the material is placed with its edge against the guide arm 26 and, as it is fed in to the skiving knife by the feed roll, the circular rib 16 forces the edge of the material out of the plane of the body portion and into the notch 58 in the presser foot 56. The material is skived in this position and when the upturned edge is bent back into the plane of the body portion two adjacent bevels will

be produced as indicated in Fig. 5, an abrupt bevel at the extreme edge of the material and a bevel of gradual inclination adjoining the abrupt bevel. The longitudinal adjustment of the gage member 20 enables the machine to produce bevels of different widths, the vertical adjustment of the presser feet provides for material of different thicknesses and the longitudinal adjustment of the carrier plate 32 and presser foot 56, in effect, varies the size of the notch 58 so that the turned up edge may have sufficient room if the stock is thick.

Having described my invention, what I claim as new and desire to secure by Letters Patent of the United States is:—

1. In a skiving machine, a knife, two members for engaging a blank of sheet material on both sides and presenting it to the knife, one of the members having a notch so located that the portion of the blank fed through it will be severed by the knife, and means including a projection on the other member and an edge gage for guiding and forcing the edge of the blank into the notch.

2. In a skiving machine, a knife, a primary presser foot, a feed device having a projecting portion to force the edge of a blank out of the plane of its body portion, and a secondary presser foot independent of the first and having a notch to co-operate with the projection.

3. In a skiving machine, a knife, a feed device provided with a projection, a presser foot for engaging a narrow section of the edge of a blank and provided with a notch, and a guide arm to co-operate with the projection in forcing the edge of the blank into the notch.

4. In a skiving machine, a knife, a feed device provided with a projection, a presser foot for engaging a narrow section of the edge of a blank, a guide arm to co-operate with the projection in forcing the edge of the blank out of the plane of its body portion, and a secondary presser foot for engaging a second section of the blank next to said narrow section.

5. In a skiving machine, a knife, a feed roll, a gage member, a plurality of presser feet, one adapted to engage the work adjacent the edge gage only and another adapted to engage the work only at a locality more remote from the edge gage, and means for adjusting the presser feet independently toward and from the feed roll.

6. In a skiving machine, a knife, a feed device, a presser member to engage one portion of the material, and a presser member inside the other to bear on another portion of the material.

7. In a skiving machine, a knife, a feed device having a projection thereon, a presser foot having a notch to receive the projec-

tion, a gage member, and an arm on the gage member to co-operate with the projection in forcing a blank into the notch.

8. In a skiving machine, a knife, a gage member, a primary presser foot, a secondary presser foot, a feed device, and means to adjust the presser feet independently towards or from the feed device.

9. A machine for operating upon a piece of sheet material, having in combination, a knife, a feed roll shaped to present the material to the knife in such manner that a scarf will be produced at the extreme edge of the material and the material reduced to a uniform thickness at the base of the scarf, and means for actuating the knife and roll.

10. A machine for operating upon a piece of sheet material, having in combination, a knife, a feed roll having two work supporting surfaces, that on the outer end being adapted to present the piece in such manner that a locality spaced slightly from the edge of the piece will be reduced to a uniform thickness and that on the inner end being raised to distort the material into a position in which it will be severed on a comparatively abrupt angle, means for actuating the knife and roll, and means for guiding the piece by engagement with the edge thereof.

11. A machine for operating upon a piece of sheet material, having in combination, cutting mechanism, and means for feeding the piece to the cutting mechanism in such manner that two scarves are formed on the margin thereof, a scarf of gradual inclination spaced from the edge of the piece, and a more abrupt scarf extending from the outer edge of the gradual scarf to the extreme edge of the piece.

12. A machine for operating upon a piece of sheet material, having in combination, a rotary skiving knife, and means for feeding the piece to the knife in such position that an abrupt scarf is produced on the extreme edge of the piece and a scarf of gradual inclination adjoining the abrupt scarf.

13. A machine for operating upon a piece of sheet material, having in combination, a knife, means for feeding the margin of the piece to the knife in position to cause the knife to produce upon the margin a bevel

of gradual inclination, and means for bending the edge of the piece toward the knife to cause a second bevel of a greater inclination to be produced simultaneously along the extreme edge.

14. A machine for operating upon a piece of sheet material, having in combination, a knife the edge of which lies all in one plane, means for feeding the margin of the piece to the knife in position to cause the knife to produce upon the margin a bevel of gradual inclination, and means for bending the edge of the piece toward the knife to cause a second bevel of a greater inclination to be produced along the extreme edge.

15. A machine for operating upon a piece of sheet material, having in combination, a knife, a roll for advancing the material to the knife, said roll having two surfaces, one raised above the other with respect to the position of the knife, independently yieldable presser feet, one located to co-operate with each surface, and means for actuating the roll and knife.

16. A machine for operating upon a piece of sheet material, having in combination, a knife, a roll for advancing the material to the knife, said roll having two surfaces, one raised above the other with respect to the position of the knife, a yieldable presser foot having an unbroken surface arranged to co-operate with the lower surface of the roll, a yieldable presser foot having a depression in its surface arranged to co-operate with the raised surface of the roll, and means for actuating the knife and roll.

17. The method of treating a piece of sheet material which consists in forming a comparatively abrupt scarf on said edge and in rendering the leather of uniform thickness in the locality at the base of the scarf.

18. The method of treating a piece of sheet material which consists in forming on the margin of the piece a scarf of gradual inclination spaced from the edge of the piece and an abrupt scarf extending from the outer edge of the gradual scarf to the extreme edge of the piece.

In testimony whereof I have signed my name to this specification.

FRANK W. CHRISTY.
